UNITED STATES PATENT OFFICE.

GRANT A. CAPRONI, OF ELGIN, ILLINOIS.

CAMP-BED.

SPECIFICATION forming part of Letters Patent No. 766,664, dated August 2, 1904.

Application filed August 14, 1903. Serial No. 169,519. (No model.)

To all whom it may concern:

Be it known that I, GRANT A. CAPRONI, a citizen of the United States, residing at Elgin, in the county of Kane and State of Illinois, have 5 invented certain new and useful Improvements in Camp-Beds; and I do hereby declare the following to be a full, clear, and exact description of the invention, such as will enable others skilled in the art to which it appertains

o to make and use the same.

My invention relates to folding or telescoping camp beds or bunks; and my object is to provide an article of this nature which will be particularly adapted for use in camp life. 5 With this object in view the tubing is preferably made of durable aluminium, and the bunk is constructed with the aid of the best quality steel pins, catches, and hinges, blued or otherwise suitably prepared against rust. The o frame is capable of being reduced within a very small compass, so that it can be readily prepared for storage and transported from place to place.

Said invention consists in the construction 5 and combination of parts hereinafter described, and more particularly pointed out in the claims.

In the accompanying drawings, illustrating the preferred embodiment of my invention, o Figure 1 is a view of the bunk ready for use. Fig. 2 is a perspective view of the frame. Fig. 3 is a plan view of the bunk with the mattress removed, showing the means of securing the bottom to the frame. Fig. 4 is a 5 view of one of the tubes, showing the catch and the notches or holes to receive the catches of the two next adjoining tubes. Fig. 5 is a full-sized view of the tubes when the telescope is closed, taken from the foot end of the bunk. The dotted lines illustrate how the catches lie. Figs. 6 and 7 are views of the catch and key, respectively; and Fig. 8 is a view of one of the cross-bars and its leg and brace.

5 Referring more particularly to the drawings, 1 is the bunk-bottom, which is preferably made of waterproofed laundried linen having a russet leather binding 1^a, binding tongues or cords of which material are adapt- ed to pass through rings 1^b, by means of

which it may be laced to the frame, as shown in Fig. 3, the cords passing around the frame and then through one of the rings, and so on until a corner is reached where the meeting ends of the cords may be tied to each other 55 or otherwise secured. Said frame is made up of telescopic side bars 2 and cross-bars 3, carrying legs 4, which in turn are provided with braces 5. The lateral bars 2 are formed of several, preferably six, telescoping tubes, the 60 smallest of which may be made solid, adapted to slide one within the other. The smallest tube is about one-fourth of an inch in outside diameter. The next tube is just large enough to neatly inclose the last tube, and is there- 65 fore about one-fourth of an inch inside diameter and has a gage of one-sixteenth of an inch, making its outside diameter about three-eighths of an inch. In this manner each tube increases its outside diameter until the first 70 tube holds them all and measures seven-eighths of an inch outside diameter. Each tube is about thirteen inches long, each, with the exception of the smallest, carries a spring- 75 catch 6, and with the exception of the largest 75 each has two notches or receivers 7 7^a, one in either end, in which the catch of the next larger tube rests. The catches, as shown in Fig. 6, are each about one-fourth of an inch wide and one-fourth of an inch long. The spring 6^a 80 is about the thickness of a clock-spring, and the plug 6^b is about one-eighth of an inch thick and must be of such shape as will fit the receivers nicely. Each catch is provided with a key- 85 hole 6^c to receive the key 8 (shown in Fig. 7) 85 for raising the catch to close the telescope in packing the bunks. These catches may be cast into the tubes or may be fastened by means of two small steel rivets, as shown in the drawings. The receivers are each one-fourth 90 of an inch to the right of its catch. For instance, the catch of the largest tube will rest in the receiver to the right of the catch in the next smaller tube when the telescope is closed, and so on. The receivers 7^a are made with 95 beveled walls, thus permitting the telescope to be drawn out without first raising the catches with the key. The other receivers are not made in this way, as it is desirable to lock the telescope in its open position.

The cross-bars 3 are formed of two parts 3^a 3^b, one adapted to slide within the other, provided with catches and receivers like those in the side bars. The hollow cross-bars 3^a are about 5 seven-sixteenths of an inch wide by five sixteenths thick and thirteen inches long and have an inside diameter large enough to neatly incase the other cross-bars, which are preferably five-sixteenths by three-sixteenths by 10 thirteen inches. On the upper surface at the outer ends of each cross-bar are suitably secured rings or loops 8, which are open at both ends on all but the head and foot bars, where the outer end is closed to keep said cross-bars 15 from slipping toward the center when the bunk-bottom is laced on. These rings or loops are preferably the same in outside measure, but the inside measure must fit the tubing. The legs 4 are fastened to the cross-bars by steel hinges 9, cast in the leg or otherwise durably fastened. Each cross-bar is provided on its lower surface with a niche 10 to receive the brace 5, which prevents the leg from closing in under the bunk when in use. 20 The hinge is so constructed that it will open just a trifle less than a right angle, thus making it necessary to "spring" it a little in order to get the brace in the niche. When not in use, the brace drops into the slot 11 in the 25 leg, which is made long enough to receive the same. The brace is preferably three-eighths of an inch thick by three-eighths of an inch wide and four and one-half inches long. The bunk may be provided with an air mattress and 30 pillow or any other suitable permanent or detachable furnishings.

I do not confine myself to the proportions and measurements herein given, as they can be varied without departing from the principle or sacrificing the spirit of my invention, and I therefore reserve the right to make any such changes in details that may fairly fall within the scope of my invention.

Having thus described my invention, what 45 I claim as new, and desire to secure by Letters Patent, is—

1. In a device of the character described, comprising a frame consisting of side bars, cross-bars having niches, said cross-bars having hinged thereto legs provided with slots, said legs having pivoted thereto braces adapted to engage said niches and when not in use, to be housed in the slots in said legs.

2. A device of the character described, comprising a frame, adapted to be reduced in size, consisting of side bars, cross-bars having niches, said cross-bars also having hinged thereto legs provided with slots, said legs hav-

ing pivoted thereto braces adapted to engage said niches and, when not in use, to be housed 6c in the slots in said legs.

3. A device of the character described, comprising a frame, having suitable supports and consisting of telescopic bars, catches, adapted to be operated by a key, on the outer surface 6c of the sections of the telescope, said catches so arranged that throughout their whole length they are flush with the outer surface of said sections, and notches or receivers in said sections adapted to receive said catches. 7c

4. In a device of the character described, a frame consisting of telescopic bars, a catch, adapted to be operated by a key carried by a section of the telescope, comprising a plate of spring metal suitably secured to said section on its outer surface and having a plug at one end normally extending into an aperture in said section and adapted to engage a corresponding aperture in the next adjoining section, said catch having a niche or dished-out portion in the outer surface of its free end for engagement by a key for withdrawing said catch. 7c

5. In a device of the character described, a frame consisting of telescopic bars, key-operated catches carried by one of the sections of the telescope, one of said sections having a notch or receiver, for said catches, provided with a beveled wall. 8c

6. In a device of the character described, a frame consisting of telescopic bars, spring-catches carried by one of the sections of the telescope, one of said sections having a notch or receiver, for said catches, provided with a beveled wall and another notch or receiver 9c with straight walls.

7. As a new article of manufacture a device of the character described, comprising a frame, having suitable supports, consisting of telescopic side bars, telescopic cross-bars having niches, said cross-bars carrying legs provided with slots, said legs having braces adapted to engage said niches and, when not in use, to be housed in said slots, the sections of the telescope having key-operated catches and notches or receivers for said catches, the frame provided with a bunk-bottom carrying a series of rings, by means of which it may be laced to said frame. 10

In testimony whereof I affix my signature in presence of two witnesses.

GRANT A. CAPRONI.
